UNITED STATES PATENT OFFICE.

WILLIAM F. SNOWDON, OF BROOKLYN, NEW YORK.

COMBINATION-WRENCH.

1,288,248.

Specification of Letters Patent. Patented Dec. 17, 1918.

Application filed March 30, 1918. Serial No. 225,721.

To all whom it may concern:

Be it known that I, WILLIAM F. SNOWDON, a citizen of the United States, residing at Brooklyn, in the county of Kings and State 5 of New York, have invented a new and useful Improvement in Combination-Wrenches, of which the following is a specification, reference being had to the accompanying drawings.

10 The object of this invention is to combine in one tool both a monkey wrench and a pipe wrench.

In the accompanying drawings:—

Figure 1 is a side view of the complete 15 tool.

Fig. 2 is a sectional view.

Fig. 3 is a face view of the pipe wrench part of the tool.

In the drawings, 1 is an extension of the 20 stationary jaw of the monkey wrench forming the stationary jaw of the pipe wrench. 2 is the movable jaw of the pipe wrench. 3 is an extension of the movable jaw of the monkey wrench that frames the movable 25 jaw 2 of the pipe wrench. 4 is a pivot on which the movable jaw 2 turns in the movable jaw frame 3. 5 is a connecting part of frame 3 against which the movable jaw 2 rests when said jaw is in neutral position.

serving to take strain from pivot 4 when the 30 tool is used as a monkey wrench. 6 is an extension of lower part of the movable jaw of the monkey wrench in which is seated a spring 7 that acts to return the movable jaw 2 to neutral position. 8 is the adjusting 35 screw of the monkey wrench which also adjusts the pipe wrench for different sizes of pipe. 9 is the stock of the monkey wrench. 10 is the free end of the movable jaw 2 to which the handle is attached. 40

Having thus described my invention, what I claim and desire to secure by Letters Patent is:—

In a combination of a monkey wrench and a pipe wrench an extension of the stationary 45 jaw of the monkey wrench forming the stationary jaw of the pipe wrench, extensions of the movable jaw of the monkey wrench forming a frame, a movable jaw pivoted in said frame, a spring tending to move said 50 pivoted jaw in one direction against said frame, a handle formed integral with said pivoted movable jaw and tending to swing said pivoted jaw in the opposite direction during manual operation of the wrench. 55

In testimony whereof I affix my signature.

WILLIAM F. SNOWDON.
